IMPROVED MAGAZINE COVER AND METHOD
OF PRODUCING SAME

William F. Grupe, Lyndhurst, N. J., assignor to
Chambon Corporation, Garfield, N. J., a corporation of New York

Application June 13, 1935, Serial No. 26,373

27 Claims. (Cl. 281—29)

This invention relates to impressed covers and to the method of production.

More particularly, the invention relates to covers for publications such as magazines and to

5 covers for other suitable articles, the cover comprising front and back cover portions of multiple ply, the exposed faces of which, that is, the obverse and reverse faces of the respective cover portions, are impressed with printed and/or other 10 matter. Preferred forms of the invention include multiple ply also at the hinge, or the backbone portion, of the cover, such portion being better known in the bookbinding art as the "back portion" of the cover.

15 Pursuant to the method of my invention, the paper or other stock in blank, and preferably in web form, is impressed upon one face only with the printed and/or other matter. The stock is then folded in such manner that the impressed 20 faces are outermost in the final product. The resulting superimposed plies may be secured to one another, preferably by bonding with adhesive, to form multiple-ply cover portions for the cover.

My invention is of especial utility in enabling 25 the desired total printing and other impressions, particularly of multi-color values, to be carried out upon one face only of the stock, and accordingly at a single operation, also affording the output of highly satisfactory products by use of 30 relatively thin stock, i. e. of lesser "point". My invention is also advantageous in that the stock material may in itself comprise multiple plies including a ply of cheaper grade as the body, and a relatively thin ply of finish grade, the printing 35 or other impressions being applied upon the finish face of the multiple ply stock. Or, an inferior grade stock may be provided on one face with a high grade finish for the reception of the impression.

40 A characteristic of covers, pursuant to my invention, resides in the fact that the terminal edges of the terminal ends of the cover portions are rounded and smooth. Such terminal edges are uncut.

45 Further features and objects of the invention will be more fully understood from the following detail description and the accompanying drawings, in which

Fig. 1 is a top plan view, largely diagrammatic, 50 showing a procedure of carrying out my invention in its web phase, followed by stages of folding and of bonding the folded portions to form the desired cover.

Fig. 2 is a side elevation of Fig. 1.

Fig. 3 is an end edge view of a type of cover

resulting from the procedure indicated in Fig. 2; this view also applies to a cover similarly formed, pursuant to my invention, from a blank in lieu of a web.

Fig. 4 is an end elevation of a magazine, including its leaves, having a cover of the type shown in Figure 3. 5

Fig. 5 is a detail end elevation of a magazine, including its leaves, having another embodiment of cover pursuant to my invention, and illustrated 10 on an enlarged scale.

Fig. 6 is an end elevation of a magazine, including its leaves, having another embodiment of cover, pursuant to my invention.

Fig. 7 is a detail perspective view of another embodiment of my invention, illustrating the principle of one or more fly leaves, printed or non-printed, as preferred. 15

The procedure indicated diagrammatically in Figs. 1 and 2, illustrates the carrying out of my 20 invention in its web phase, a form of my invention which possesses especial economies in the commercial utilization of my invention, as is apparent. However, as hereinabove and hereinbelow set out, my invention is not limited to such web 25 phase of its utilization, and is applicable, inter alia, to the phase of individual blanks treated in a manner corresponding with the web phase of my invention.

Referring to Figs. 1 and 2, 10 indicates a web 30 of paper or other suitable stock, which has been printed as is indicated at 10a. It will be understood that each and all of the spaces 10a' are likewise printed or otherwise impressed, the repetition of the consecutively repeated printed or 35 other impressed matter being omitted for convenience. The lines 10a'' indicate the margins between the repeated printed areas.

11 represents an adhesive applying roller and 40 12 its complementary pressure roller, adhesive being applied to the effective face of the roller 11 by any suitable means, such as an applying roll 13 contacting in turn with the effective face of the roller 11 and the face of the feed roller 14, which last named may be partly immersed in 45 a bath 15 of the adhesive contained in the reservoir 16, or the equivalent of the above. By such or other approved procedure, adhesive is applied to the unprinted face 10b, see Fig. 2, of the web 10. 50

Subsequent to the stage of application of adhesive, the laterally opposite margins of the web, indicated at 10c, are folded inwardly against the mid-portion of the web so that unimpressed faces of the web are contiguous, the folding and the

bonding of the juxtaposed adhesive applied faces being completed by one or more sets of complementary pressure rolls 17.

The thus or otherwise folded and bonded web portions are then severed by suitable severing means at the marginal lines 10a'', as by a set of complementary severing rolls 17a, thus yielding individual covers. A severing blade is indicated at 17b.

10 Correspondingly, in carrying out the blank phase of the invention, individual blanks of the full width, are appropriately printed or otherwise impressed upon one face, adhesive applied to the under, i. e., unimpressed face and laterally opposite portions respectively folded to form the desired cover.

One type of cover, pursuant to my invention, is indicated in Fig. 3, the desired printing or other impressions appearing on one or both faces 20 10a, as optionally preferred, of the front and back cover portions. In Fig. 3 there is indicated at 18 a reduced thickness of the cover, appropriately and herein termed the hinge or backbone of such cover. The backbone portion of the type shown 25 in Fig. 3 is effected by spacing the terminations, i. e. edges, see 10e, 10e, from one another. The backbone thus comprises one ply of the material whereas each cover portion comprises two plies.

A magazine having the type of cover shown in 30 Fig. 3, is indicated in Fig. 4, its leaves 19, usually comprised of one or more signatures, stapled, sewed or otherwise bound to one another, being suitably secured at their aligned edges 19a to the backbone 18. The securing is preferably of 35 permanent form for the life of the magazine.

As is indicated in Fig. 1 by the manner of folding of the edges 10e, namely in butt to butt relationship, each individual cover results in the type indicated in Fig. 5, namely, having its backbone 40 portion 18' of double, i. e., the same number of plies as the respective folded cover portions, the leaves 19 of the book, of one or more signatures, or equivalent, being suitably permanently secured, see 19a, to such backbone portion 18' of 45 the cover.

In Fig. 6 is shown another type of cover, namely, providing for overlapping at the backbone portion of the cover, thus effecting an increased 50 number of plies at the backbone portion 18'' of the resulting cover as compared with the number of plies of each cover. Such form of cover is particularly applicable for magazines and the like, the leaves 19 of which are secured by staple, see 20, or other mechanical form of attachment 55 to the cover, the increased number of plies at the backbone portion enhancing such mechanical attachment.

Recurring to the type of cover shown in Figs. 3 and 4, the widths of the inner plies of the cover 60 portions are, respectively, less than one-fourth of the total width of the web or the blank. In the type of cover shown in Fig. 5, the widths of the inner plies of the cover portion, are exactly one-fourth of the total width of the web or the blank.

65 In the type of cover shown in Fig. 6, the widths of the inner plies of the cover portions are, respectively, greater, to a desired extent, than one fourth of the total width of the web or the blank.

It will be observed that in the above embodiments of my invention, the eventual terminal edges, see 21, of the terminal ends of the cover portions by reason of the stated folding operations, are each rounded and smooth, thus avoiding the so-called "raw" edges inevitably ensuing 70 upon cutting or other severing operation.

It is apparent that each cover portion may be formed of a number of plies in excess of two by suitable folding, the printing being confined to the portions of the blank or web which eventually become the inner and outer faces, that is, the 5 reverse and obverse faces, of the respective cover portions.

My invention may also afford an integrally connected fly leaf for each or both of the respective front and back cover portions, by providing 10 sufficient additional width of the web or the blank. Applied to the type of cover shown in Figs. 3 and 4, and as indicated in Fig. 7, the two fly leaves 22 extend freely from the lines of terminations 10c'. One face of each such fly leaf, 15 i. e., that face which is coincidental with the printed faces of the cover portions, may also be printed, if desired.

Economy in cost of material and also increased tensile, shearing and puncture strengths, as well 20 as enhanced quality of product are attained, by the laminated structure of the front and the rear cover portions, in which, incidentally, thinner than usual stock may be utilized. Individual plies are serially and integrally connected. The intervening layer of adhesive may be selected and applied to enhance the degree of flexibility or rigidity of the resulting laminated structure.

It should be noted that the present invention refers to covers which are adapted to positively 30 bind suitable inserts such as publications, blank sheets, book-matches and articles having generally similar characteristics. For this purpose, each cover pursuant to this invention is provided with a back portion which integrally connects 35 multiple-ply cover portions and provides hinge action for the cover portions relative to each other, and, pursuant to the method of this invention, the blank after being formed, is folded to produce the desired line of hinge in providing 40 the resulting cover with the required back portion and with integrally related cover portions for the reception and the securing in book formation, of a suitable insert.

It is advantageous that the back portion of 45 the cover be formed at and along that portion of the blank or web at which the original lateral edges thereof are located after the first folding and securing operations. That is to say, that intermediate location in the blank or web at 50 which those edges of the blank or web which were the original lateral edges thereof, just meet or are spaced apart, or overlap, pursuant to the preferred type of folding operation afore-described in detail, is ideally adapted to become the 55 back portion of the cover for the reception and positive securing of the insert.

Whereas I have described my invention by reference to specific forms thereof it will be understood that many changes and modifications may 60 be made without departing from the spirit of the invention as defined herein and in the claims that follow.

I claim:

1. The method of producing a cover of the 65 character described, which comprises impressing one face of a blank of sheet material, forming multiple ply cover portions integrally hinged to each other through the medium of a cover back portion by folding the blank upon itself so that 70 impressed face portions are faced outwardly, and securing the folded over part to the main part of the blank.

2. The method of producing a cover of the character described, which comprises impressing 75

one face of a blank of sheet material, forming multiple ply cover portions integrally hinged to each other by folding the blank upon itself so that impressed portions are faced outwardly, and 5 by bonding the folded over part to the main part of the blank by interposing adhesive between contiguous faces, and folding the so-prepared blank to form a cover having an insert-receiving back portion.

10 3. The method of producing a cover of the character described which comprises impressing one face of a blank of sheet material, forming multiple ply cover portions integrally hinged to each other through the medium of a cover back 15 portion by folding one set of laterally opposite margins of the blank inwardly against the mid-portion of the blank so that impressed faces are faced outermost, and securing the said margins in their new positions.

20 4. The method of producing articles of the character described which comprises impressing one face of a web of sheet material, continuously folding the laterally opposite margins of the web inwardly against the mid-portion of the web so 25 that impressed faces thereof are faced outermost, continuously securing the said margins in their new positions, successively severing individual covers from the so folded web across the width thereof, and folding the so-prepared blanks to 30 form covers having insert-receiving back portions, respectively.

5. The method of producing multiple ply covers of the character described, each having multiple-ply cover portions which are integrally hinged to 35 each other through the medium of a cover back portion, which comprises impressing one face of a web of sheet material, applying adhesive continuously to the opposite face of the web, continuously folding the laterally opposite margins 40 of the web inwardly against the mid-portion of the web so that impressed faces are faced outermost, continuously pressing the adhesively coated contiguous faces together, and successively severing individual covers from the so folded web 45 across the width thereof.

6. A cover of the character described, comprising multiple ply cover portions integrally hinged through the medium of a cover back portion, the individual plies of respective cover portions being 50 serially and integrally connected and secured to one another in their superimposed positions, and the hinged back portion being of the same ply as the cover positions.

7. A cover of the character described, comprising multiple ply cover portions integrally hinged through the medium of a cover back portion, the individual plies of respective cover portions being 55 serially and integrally connected and bonded to one another in their superimposed positions by interposed layers of adhesive, and the hinged back portion being of the same ply as the cover positions.

8. A cover for publications, comprising multiple ply cover portions integrally hinged through the medium of a cover back portion, the individual plies of respective cover portions being secured to one another and being integrally connected at the terminal edge of their terminal ends to provide a rounded edge, for such terminal edge, 60 which is smooth and blunt.

9. A cover as recited in claim 8 wherein the individual plies of respective cover portions are bonded to one another by adhesive.

10. The method, as recited in claim 3, of producing a cover of the character described, where-

in the stated folding operation is so carried out that the terminal edges of the said margins which are folded, fall short of meeting by approximately the desired width of the back portion of the resulting cover. 5

11. The method, as recited in claim 3, of producing a cover of the character described, wherein in the stated folding operation is so carried out that the terminal edges of the said margins which are folded, just meet. 10

12. The method, as recited in claim 3, of producing a cover of the character described, wherein in the stated folding operation is so carried out that the terminal edges of the said margins which are folded, overlap by approximately the desired 15 width of the back portion of the resulting cover.

13. A method, as recited in claim 4, of producing multiple-ply covers of the character described, wherein the stated folding operation is so carried out that the terminal edges of the folded margins fall short of meeting by approximately the desired width of the back portion of a resulting cover. 20

14. A method, as recited in claim 4, of producing multiple-ply covers of the character described, 25 wherein the stated folding operation is so carried out that the terminal edges of the folded margins just meet.

15. A method, as recited in claim 4, of producing multiple-ply covers of the character described, 30 wherein the stated folding operation is so carried out that the terminal edges of the folded margins overlap by approximately the desired width of the back portion of a resulting cover.

16. A method, as recited in claim 5, of producing multiple-ply covers of the character described, 35 wherein the stated folding operation is so carried out that the terminal edges of the folded margins fall short of meeting by approximately the desired width of the back portion of a resulting 40 cover.

17. A method, as recited in claim 5, of producing multiple-ply covers of the character described, wherein the stated folding operation is so carried out that the terminal edges of the folded margins 45 just meet.

18. A method, as recited in claim 5, of producing multiple-ply covers of the character described, wherein the stated folding operation is so carried out that the terminal edges of the folded margins 50 overlap by approximately the desired width of the back portion of a resulting cover.

19. The method of producing a cover of the character described which comprises impressing one face of a blank of sheet material, forming 55 multiple-ply cover portions integrally hinged to each other through the medium of a cover back portion by folding one set of laterally opposite margins of the blank inwardly against the mid-portion of the blank so that impressed faces are 60 faced outermost, and bonding the folded margins to the mid-portion of the blank by interposing adhesive therebetween.

20. The method, as recited in claim 19, of producing a cover of the character described, wherein 65 the stated folding operation is so carried out that the terminal edges of the said margins which are folded, fall short of meeting by approximately the desired width of the back portion of the resulting cover. 70

21. The method, as recited in claim 19, of producing a cover of the character described, wherein the stated folding operation is so carried out that the terminal edges of the said margins which are folded, just meet. 75

22. The method, as recited in claim 19, of producing a cover of the character described, wherein the stated folding operation is so carried out that the terminal edges of the said margins which are folded, overlap by approximately the desired width of the back portion of the resulting cover.

23. The method of producing magazine covers bearing legible matter upon the respective obverse and reverse faces of each cover, which comprises repeatedly impressing the desired legible matter at intervals upon one face of a web of material of the nature of paper, continuously folding the laterally opposite margins of the thus impressed web inwardly, so that impressed faces are faced outwardly, the respective lines of fold being spaced from the lateral edges of the web approximately one-fourth of the total width of the web, securing the so folded margins of the web in their new positions, and severing the so folded web at the margins of the repeated impressions.

24. A cover of the character described comprising multiple ply cover portions integrally hinged, the individual plies of respective cover portions being serially and integrally connected and secured to one another in their superimposed po-

sitions, and the hinge portion being of greater ply than the cover portion.

25. A cover of the character described comprising multiple ply cover portions integrally hinged, the individual plies of respective cover portions being serially and integrally connected and bonded to one another in their superimposed positions by interposed layers of adhesive, and the hinge portion being of greater ply than the cover portions.

26. A cover of the character described comprising multiple ply cover portions integrally hinged, the individual plies of respective cover portions being serially and integrally connected and secured to one another in their superimposed positions, and the hinge portion being of lesser ply than the cover portion.

27. A cover of the character described comprising multiple ply cover portions integrally hinged, the individual plies of respective cover portions being serially and integrally connected and bonded to one another in their superimposed positions by interposed layers of adhesive, and the hinge portion being of lesser ply than the cover portions.

WILLIAM F. GRUPE.
